(57) **CLAIM**

The ornamental design for a vehicular push bumper with light mounting receptacles, as shown and described.

DESCRIPTION

FIG. 1 is a front perspective view of the vehicular push bumper with light mounting receptacles of the present invention showing my new design with the dotted lines depicting solely environmental structure and forming no part of the claimed design;

FIG. 2 is a front elevational view thereof;

FIG. 3 is a top plan view thereof;

FIG. 4 is a left side view thereof;

FIG. 5 is a right side view thereof;

FIG. 6 is a rear elevational view thereof; and,

FIG. 7 is a bottom plan view thereof.

1 Claim, 3 Drawing Sheets**FIG. 1****FIG. 2**

FIG. 3**FIG. 4****FIG. 5**

FIG. 6**FIG. 7**
